CLAIM

The ornamental design for a hair dryer, as shown and described.

DESCRIPTION

FIG. 1 is a perspective view of a hair dryer, shown in a used condition showing my new design;

FIG. 2 is a front, left and bottom perspective view thereof;

FIG. 3 is a front, left and top perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the hair dryer and the hair dryer attachments shown in FIG. 1 form no part of the claimed design.
